A. FACCI

SQUARE, PLUMB, LEVEL, AND MEASURE

Filed April 7, 1926

INVENTOR
Anthony Facci.
BY
H. R. Johns.
ATTORNEY

UNITED STATES PATENT OFFICE.

ANTHONY FACCI, OF HASTINGS, PENNSYLVANIA.

SQUARE, PLUMB, LEVEL, AND MEASURE.

Application filed April 7, 1926. Serial No. 100,321.

This invention relates to a combined level and square, and has for its object to widen the field of utility for such a tool, thus enhancing its salability.

5 According to this invention a square is provided with a series of leveling means, preferably located in one of its sides, and so arranged that the tool may be used to level with either edge of either side of the square 10 uppermost. Additionally the bubble tubes or other leveling means are preferably readable with either face of the square uppermost, whereby when one side of the square is made thinner than the other, to enable 15 the tool to be used simultaneously for squaring and leveling with the thin side.

Referring to the drawing:

Fig. 1 is the preferred embodiment of my invention.

20 Fig. 2 is the side view of the upper portion of Fig. 1, but with the edge bubble tube 20 located a little nearer the vertex.

Fig. 3 is the section on the line 3—3 of Fig. 1.

25 In the illustrated embodiment the square is provided with a thick side 1, having its other side 2 thinner and inserted between the faces of the thick side. As is usual in the art appropriate measuring graduations are 30 provided on the outer edges of both sides. Within the side 1 are located two pairs of bubble tubes 10, 11, 12, and 13, the tubes of each pair being parallel and the pairs being at right angles, in other words parallel with 35 each side for leveling with either side. Apertures 3, 4, 5, and 6 above each bubble tube facilitate reading the bubble. For convenience another leveling tube 20 is arranged adjacent with the inner edge of the side 1 40 and is protected by a guard plate having an opening 21 therein through which the position of the bubble is read.

In operation the bubble tubes illustrated 45 permit leveling with either side of the square and with either edge of either side uppermost. For example, if the side 1 of the square is used as a level with the edge 14 on the work then tube 10, which is observable from either side or above, indicates when 50 the work is level. If the edge 15 of the side 1 is down on the work and the side 14 uppermost the bubble tube 11 can then be read

from either side or above. If the outer edge 17 of the short side of the square is against the work and down, tube 13 is read 55 in a manner similar to that for reading the former tubes. If the edge 16 of the short side is placed against the work or when, for example, the outer end of the long side 1 is placed on a support for the purpose of sight- 60 ing along the edge 17 to tell whether some object is level, the tube 12 is read. When leveling with the edge 15 down against the work the tube 20 may be easily read if the workman's eye is over the work. Since, as 65 illustrated, the bubble tubes are observable from either face 18 or 19 of the side 1, it will be apparent that since the side 2 of the square is thinner and a shoulder formed be- 70 tween side 2 and faces 18 and 19, that this 70 tool may be used for squaring with that side on top of the work and side 1 having its edge 14 contiguous to an edge of the work, while simultaneously leveling with side 2 and reading either of tubes 12 or 13. 75

I claim:

1. A square comprising in combination a plurality of leveling means arranged for leveling with either edge of either side of the square uppermost and an additional 80 leveling means on the edge of one side.

2. A square comprising in combination a plurality of leveling means arranged for leveling with either edge of either side of the square uppermost and said leveling 85 means being readable from either face of and within one side of the square.

3. A square comprising in combination a plurality of leveling means arranged for leveling with either edge of either side of 90 the square uppermost and within one side of the square.

4. A square having its sides rigidly and permanently connected and comprising in combination a plurality of leveling means 95 arranged for leveling with either edge of either side of the square uppermost and within one side of the square intermediate the edges thereof.

5. A square comprising in combination a 100 plurality of leveling means arranged for leveling with either edge of either side of the square uppermost, one side of the square being thin and placed between the planes of

the faces of the other side of said square and with a shoulder between the thin side and either face of the thicker side of the square.

6. A square having one of its sides substantially longer than the other and comprising in combination a plurality of leveling means arranged for leveling with either edge

of either side of the square uppermost, said leveling means comprising two pairs of bubble tubes, those of each pair being ¹⁰ parallel, and the pairs being normal to each other and intermediate the edges of the long side of the square.
